UNITED STATES PATENT OFFICE.

GEORGE A. OLIVER, OF CLEBURNE, TEXAS.

GRINDING MACHINE.

Application filed November 21, 1925. Serial No. 70,479.

This invention relates to improvements in grinding machines and has special reference to a machine for reclaiming universal cylinder packing ring segments.

5 The railroads have quite generally adopted for use in their locomotives what is known as the universal cylinder packing rings. These rings are made in two circular parts each part consisting of a plurality (usually six) of segmental portions. The two parts are grooved in their adjacent sides, for the reception of an internal spring ring which serves to hold them in place and to set them against the interior walls of the cylinders. When the engine is shopped for repairs or general overhauling, the worn rings are trued up so as to properly fit the bore of the cylinders and replaced.

10 It has been found from experience that it is extremely difficult to assemble the various segments of which the ring is composed into a full ring and to turn or grind them as a ring because the ends of the segments are worn so that if they are placed end to end, the ring becomes distorted and of a smaller diameter than that required. If the segments are assembled so as to form a circular ring of the required diameter, a splice piece must be added; thus, for example, if 15 the rings are made up of six segments each subtending an arc of sixty degrees, then when the splice piece is added there will be seven segments in each part, but the ring will now have the proper diameter and will therefore fit as well as when the rings were new.

20 It has hitherto been customary to save all the removed segments of this type for packing rings and to ship them to a reclamation plant where they were matched up with reference to the semicircular groove. These 25 grooves, however, become worn and distorted and all packing rings thus assembled were imperfect and did not fit the cylinder thereby permitting a waste of steam and causing 30 a decreased efficiency.

When rings are assembled from old parts in the usual manner, the segments with tapered ends have to be scrapped and as this 35 is true of about one-half of the segments, a large loss results. When the machine that 40 forms the subject matter of this invention is employed, the segments may have their ends ground off so as to remove any taper thereby making it possible to save all of 45 the ring segments however worn they may be.

My invention, briefly described, comprises a base upon which I have mounted a grinding wheel which is rotated about its axis by some suitable means such as an electric 60 motor, a steam turbine or by means of power transmitted to it by a belt. Mounted so as to swing about a pivot that intersects the axis of the grinder is a plate that can be oscillated about this pivot while moving in 65 a plane parallel with the axis about which the axis about which the grinding wheel turns, means is provided for moving the plate towards and away from the grinder so as to obtain any desired distance between the 70 pivot of the plate and the grinding surface. The segments that are to be reclaimed are fastened to the upper surface of the oscillating plate and adjusted so as to be concentric with the pivot about which the plate 75 rotates. The pivot is then adjusted with respect to the grinding surface so as to get the desired radius.

In order to describe my invention so that its construction and the manner of using the same shall be clearly understood, I shall have reference to the accompanying drawings in which one specific embodiment thereof has been illustrated and in which:

Fig. 1 is a top plan view of my improved 85 machine;

Fig. 2 is a side elevation thereof;

Fig. 3 is a section taken on line 3—3 of Fig. 1;

Fig. 4 is a section taken on line 4—4, 90 Fig. 2;

Fig. 5 is a section taken on line 5—5, Fig. 1;

Fig. 6 is a section similar to that shown in Fig. 5 but which illustrates a modification; 95

Fig. 7 is a section taken on line 7—7, Fig. 2;

Fig. 8 is a view looking in the direction of arrow 8 in Fig. 1 and shows the manner in which the adjusting bolt is locked in adjusted position, and 100

Fig. 9 shows the manner in which the swinging table or radius plate can be extended to take care of large sized rings.

Numeral 1 represents the base of my 105 machine. This base is supported on four legs 2 which hold the base at the desired height above the floor 3. Secured to the upper surface of the base 1 are two pillow blocks 4 and 5 within the bearings of which the shaft 6 is journalled. This shaft may be rotated by any suitable means such as a

steam turbine motor or belt but as an example I have shown an electric motor 7 directly coupled to the shaft at 8. A grinding wheel 9 is fastened to one end of the shaft. The upper surface of the base 1 has a depression 10 directly underneath the grinding wheel so that wheels of varying diameters may be used. This depression has sufficient width in the direction of the shaft to permit the grinding wheel 9 to be readily removed and replaced. The end of the base adjacent the depression 10 has its upper surface at such a height that the plane of the upper surface 11 thereof intersects the wheel 9 the desired distance below its axis. A T slot 12 is provided in the material beneath the surface 11. This slot extends parallel with the axis of the shaft 6 and is symmetrical with respect to a vertical plane that passes through the axis of the shaft so that the head 13 of the T-bolt 14 can be moved only in a direction parallel with the axis of the shaft 6. The head 13 of the bolt 14 is elongated and one end thereof has a vertical T-slot 15 for the reception of the head 16 of the adjusting screw 17 which cooperates with a threaded opening in the nut 18 which is secured to the end of the base by means of bolts 19. Secured to the end of the screw 17 is a handle 20 by means of which it can be rotated. It is evident that if it is found desirable the screw 17 may have a threaded connection with the head 13 and be rotatably but nonslidably connected with the part 18. In the construction illustrated the bolt 14 can be moved to any desired position along the slot 12. In order that the bolt shall not be permitted to rotate accidentally, I have so constructed the nut 18 that the screw can be clamped against rotation. This is accomplished by providing the nut with a cut 21 which intersects the threaded opening and divides one end into two sections 22 and 23. A clamping bolt 24 has a threaded connection with the section 22 and is rotatable in the hole in section 23 so that when the bolt is rotated in one direction it tends to close the cut 21 and clamp screw 17 against rotation. The bolt 14 has a portion 25 thereof, directly above the head 13, cylindrical; this cylindrical portion extends above the surface 11 a distance slightly less than the thickness of the radius plate 26 where it terminates in a shoulder 25^a whose width is equal to the difference between the diameter of the cylindrical part 25 and that of the threaded part 14. The radius plate 26 is sector shaped (Fig. 1) and has a hole 27 into which the cylindrical part 25 extends. The arcuate edge 28 of plate 26 is curved about the center of the hole 27. A washer 29 has a central opening 30 for the reception of the threaded part 14 and is provided on its lower side with a downwardly projecting circular flange 31 that rests upon the shoulder 25^a. A nut 32 that is provided with a handle 33 is threaded onto the bolt 14. By means of the flange 31 it is possible to obtain the desired clearance between the plate 26 and the washer 29 whereby the plate 26 may be rotated about the pivot 25; a handle 34 being attached to the plate to facilitate movement thereof. Secured to the bottom of the depression 10 is a support 35 which can be removed by removing the bolts 36 and which serves as a support for the end of the plate 26. The bolts 36 pass through elongated slots 37 in the support so that it may be adjusted towards and away from the wheel 9. Plate 26 has secured to it two stud bolts 38 which are employed for clamping the ring segment 39 in place. The ring segments have a cross section substantially like that shown in Figs. 5 and 6 and have a semicircular groove 40 on one side. I have shown two ways in which the rings 39 may be secured in place. In Fig. 5 I have shown a clamp 41 that has one end slotted for the reception of the clamping bolt 38 and the other end curved so as to provide a hooked end 43 that engages in the groove 40. A spacer 44 is applied to the bolt between the clamp 41 and the upper surface of the plate 26. In Fig. 6 I have shown a slightly different clamping means. In this clamping device the clamps 41 have been replaced by clamping members 45 which have a straight portion provided with a longitudinal opening 47. One end of members 45 is bent at right angles, in the manner indicated by numeral 48. The end of part 48 rests upon the upper surface of the plate 26 and the other end of the clamping member rests upon the cylindrical bar 49 that lies in the groove 40. By tightening the nut on bolts 38 the ring 39 may be clamped against the surface of the plate 26. In order to be able to conveniently adjust the ring 39, the ends 48 have been provided with threaded openings for the reception of screws 50 whose ends abut the rings in the manner clearly shown in Fig. 6. Where segments of exceptionally large radii are to be ground, it is sometimes necessary to attach to plate 26 an arcuate extension 51 (Fig. 9) which has elongated openings 52 for the reception of the clamping bolts 38 and is provided with bolts 53 that correspond in function with bolts 38 and cooperate with the clamp 54 in holding the member, to be ground, in place.

The operation of my machine is as follows: Let us suppose that it is desired to true a number of segmental ring sections 39 of a given radius which we will designate as "R." The plate 26 is adjusted by means of the screw 17 until the distance between the face of the grinding wheel and the center of the bolt 14 is equal to the radius desired.

Screw 24 is now tightened so as to prevent accidental rotation. One of the ring segments 39 is now laid upon the plate 26 and adjusted so as to be concentric with the 5 pivot 14 and then clamped against movement by the means already described. The grinding wheel is now set into motion and the plate 26 oscillated so as to bring all parts of the periphery against the grinding 10 surface of the wheel. The plate 26 can be rotated through as great an angle as may be necessary and the rings can be readily calipered so as to facilitate obtaining the proper radius.

15 Although I have shown my invention embodied in a machine having a unitary base member, it can be constructed in other ways and even made in the form of an attachment to an ordinary lathe.

20 By adding the extension plate 51 (Fig. 9) it is possible to grind arcuate members of much greater radii than cylinder rings.

Having now described my invention, what I claim as new is:

A grinding machine for grinding arcuate segments to a predetermined radius of curvature comprising, in combination, a base member having a plurality of bearings, a shaft mounted for rotation in said bearings, a grinding wheel secured to said shaft, said 25 wheel having a plane grinding surface, a plate supported by said base and mounted for oscillation in a plane perpendicular to the plane of the grinding surface of the wheel, a pivot about which said plate oscillates, means for moving said pivot towards and away from the grinding wheel, means for supporting the outer end of said plate and an arcuate extension plate secured to the movable end of said first mentioned 30 plate.

In testimony whereof I affix my signature.

GEORGE A. OLIVER.
